INSULATED HOUSING FOR GAS HOLDERS

Ferguson Barnes, Bexley, Ohio, assignor to International-Stacey Corporation, Columbus, Ohio, a corporation of Ohio

Application December 22, 1939, Serial No. 310,648

10 Claims. (Cl. 220—15)

This invention relates to holders for gaseous fluids and is particularly directed to means for insulating and protecting such holders from damage resulting from freezing.

In their ordinary form, large gas holders are formed to include an open-topped vessel section and an inverted cup-like drum section telescopically positioned in the first section, the lower being filled with water to seal the open lower end of the movable section and prevent the escape of the gas contained therein. As gas is introduced or withdrawn from the holder, the inverted section raises or lowers in proportion to the amount inserted or withdrawn. In localities where lower temperatures prevail during certain seasons of the year, the water in the stationary section is apt to freeze and damage the holder either by bursting the sections or obstructing the upper section in its movement. To avoid this danger, it has been proposed to heat the water in the holder to prevent ice formation. This practice has disadvantages, however, since the holders are of such size that considerable expense is involved in elevating the temperature of the water and maintaining it at the elevated temperature, the radiating surface of the holders being so extensive.

The primary object of this invention resides in providing housing means for stationary section of a gas holder and insulating such housing means to prevent the escape of heat contained within the water in the gas holder. By this provision, the heat required to maintain the elevated temperature of the water will be reduced and the required length of time for heating diminished.

Another object of this invention rests in forming the insulating housing of sections which can be assembled and dismantled in the field to permit the application of the housing to gas holders already in use.

A further object resides in forming the housing in such manner that a minimum number of connections will be required to secure the housing to the gas holder so that the labor expended in assembling and installing the housing will not increase the cost to such an extent as to make use of the housing prohibitive.

A still further object is to construct the housing of relatively light materials and so connect and mount the various parts of the housing that the original framework of the gas holder will effect the support of the housing, thus decreasing the cost of the housing by eliminating the necessity of providing a separate supporting

frame and employing relatively heavy materials in the construction of the housing.

Another object rests in making the housing of sections and connecting them at the edges thereof by tie bars, then utilizing the gas holder itself as a reinforcing medium by employing a plurality of stress bolts which are threadedly carried by the housing and are adjusted to bear against the gas holder and apply an outward thrust to the housing. When strong winds engage the housing, sufficient resistance to crushing or buckling will be exerted even though the housing is formed from light weight materials.

For a further understanding of the invention, attention is directed to the following description and the accompanying drawings in which the invention has been illustrated in its preferred form.

In the drawings:

Fig. 1 is a perspective view of a gas holder supplied with the insulating housing constructed in accordance with the present invention;

Fig. 2 is a fragmentary side elevational view of the housing on a slightly enlarged scale;

Fig. 3 is a vertical sectional view taken through the housing on the plane indicated by the line III—III of Fig. 2;

Fig. 4 is a detail side elevational view of the portion of the housing shown in Fig. 3;

Fig. 5 is a detail sectional view taken on the plane indicated by the line V—V of Fig. 4;

Fig. 6 is a detail sectional view illustrating the connection between the edge portions of the panels and the columns employed to support the superstructure of the gas holder;

Fig. 7 is a detail vertical sectional view taken on the plane indicated by the line VII—VII of Fig. 6.

Fig. 8 is a detail horizontal sectional view illustrating slightly modified mechanism employed to reinforce the housing and apply outwardly directed thrust forces thereto.

Referring more particularly to the drawings, the numeral 1 designates the gas holder in its entirety. As usual, the gas holder includes a stationary base section 2 which is open at its upper end to telescopically receive the inverted movable upper section 3 of the holding mechanism. The section 2 is quite similar to a pan in that it receives a body of water which prevents the escape of gas from the interior of the upper section 3 around the lower edge thereof. This edge is immersed in the liquid at all times. As previously mentioned, the object of the housing, indicated generally by the numeral 4, is to prevent the liquid contained within the section 2 from

freezing during periods when reduced temperatures prevail.

At the upper end of the stationary section, the usual walkway 5 is provided, this structure being supported in part by vertically extending columns 6 disposed in circumferentially spaced order around the stationary section. The columns are generally formed from structural members having I-sections as indicated at Fig. 6 in the drawings.

The housing comprising the invention includes a plurality of units, each of which is disposed between adjacent pairs of the columns 6. Each unit is formed from a plurality of panel sections 7 joined at their edges to form the unit which is in turn connected at its edges with columns 6 and the under side of the walkway 5. Each of the units 7 includes a plurality of the panels, certain of which are smaller in size than the remaining panels. All of the panel sections include frame members 8 formed of angle bars joined at their ends to form a rectangular structure for the reception of metallic and insulating sheets 9 and 10 suitably secured to the frame structures.

The walkway 5 has angular bracket members 11 secured to the under sides thereof between the columns 6 and the vertical flanges of the bars 11 are provided with slots 12 to receive bolts 13 employed in holding additional angle bars 14 thereto. The horizontal flanges of the bars 14 are provided at spaced intervals with the stationary portions of hinge members 15. The movable portions of these members are secured to certain of the smaller panels. When the movable parts of the hinge are joined with the stationary parts by pivot pins 16, the small panels may be moved about horizontal axes to vent the upper portion of the housing.

Vertically extending bracket bars 17 are connected with the members 11 and have their lower ends connected with the upper ends of the upper row of larger panel sections as at 18. The lower row of large panel sections are bolted to the lower edges of the panels in the upper row by bolts 19 extending through the horizontal flanges of the panel frames. The outer edges of the horizontal flanges of the upper panel frames are formed with a down-turned lip 20 which seals the joint between the edges of the panels and prevents the entrance of cool air between the horizontal edges of the panels.

In the present illustration, each unit is composed of three groups of superposed panel sections which are rigidly connected at their horizontal meeting edges, the groups being joined to one another at their vertical edges by transversely extending tie bars 21. These bars are of a sufficient length to space the side angle bars of the panels at a slight distance. To secure the tie bars to the panels, the angle bars, at or near the corners of the panels, are provided with lugs 22 having perforations formed therein to receive bolts 23. These bolts extend through perforations formed in the ends of the tie bars 21.

To prevent entrance of cool air into the housing through the space between the panel sections, an insulating strip 24 is positioned therein, the side edges of the strip engaging the frame members of the panel sections. These insulating strips are maintained in position by flashing strips 25 supported by the bolts 23. The flashing strips are provided at their longitudinal edges with inwardly extending flanges 26 which fur-

ther prevent air from entering the housing and reinforce the flashing strips.

At the side edges of the housing units formed by the panel sections, the frames 8 of the panel sections have angle lugs 27 rigidly secured thereto by bolts or other fastening means 28 which pass through the lugs secured to the angle bars of the panel frames. The angle lugs 27 have outwardly directed flanges 29 formed with perforations for receiving bolts 30 which extend through openings formed in the bodies of the columns 6. The bolts 30 extend through the angle brackets of the panel units on each side of the column and secure the panel units in firm relation with the column. After the panel units are thus bolted in place, the open edges of the joints may be packed with oakum or other insulating material and the bolts then further tightened to securely clamp the edges of the panel units against the insulating material.

To hold the hinged panels in a closed position, vertically extending straps 31 are connected with the upper row of large panels and lugs provided at the lower edge of the hinged panels.

To vent the housing, these straps may be removed and the hinged panels moved to an open position indicated in dotted lines in Fig. 3 where they may be held by a brace rod 32 carried by the angle bars 17. At their lower ends, each group of superposed panels engage the vertical flanges 33 of angle bars suitably secured to the foundation of the gas holder. Any desired means may be employed to maintain the engagement of the panels with the flanges 33, the connection should permit relative vertical movement between the panels and the flanges 33 to compensate for expansion and contraction of the panel sections.

The materials from which the panels are formed may be of relatively light weight to keep the manufacturing cost of the housing at a minimum figure and to decrease the weight supported by the columns and the walkway. To increase the strength of the housing and prevent buckling thereof under exteriorly applied pressures, certain of the tie bars 21 are provided with threaded openings to receive thrust screws 34 which extend through the spaces between the groups of panels and engage the outer surface of the stationary section 2 of the gas holder.

From Fig. 5, it will be apparent that when the screws 34 are threaded inwardly, the inner ends thereof will bear against the stationary section 2 and an outward force will be exerted on the panels. This force will place the panels under a stress and prevent inward movement thereof when external pressures are applied. The adjustment of the screws 34 will be maintained by jamb nuts 35 carried by the screw and engaging the outer surfaces of the tie bars.

To assist in the installation of the housing, the upper panel of each group is provided with a pair of eye bolts 36 through which cables may be trained to elevate the panels and hold them until the bolts 30 may be put in position. By constructing the housing as herein described, the labor necessary in installing the housing may be reduced to a minimum figure, the only operations required to be performed in the field being the drilling of holes in the columns 6 and the walkway. To prevent the sheets 9 and 10 from deformation, horizontally extending brace members 37 are provided which are formed from structural steel and attached to the frame structure 8 in any suitable manner.

By pivotally mounting the narrow panel sec-

tions at the upper portion of the housing, these sections may be moved to open positions when desired to ventilate the space between the housing and the container. This feature has been found quite important since it lessens the tendency of the container to sweat and consequently to prematurely deteriorate. It is obvious that means other than the pivoted panels could be employed for ventilating purposes with equal facility, the present showing being merely indicative of one manner in which the ends desired may be secured.

Through the construction disclosed, the housing sections may be readily dismantled when it becomes necessary to paint or otherwise service the container.

It is also within the possibility of the invention to keep the housing spaced from the outer surface of the tank a distance sufficient to permit workmen to enter the space to perform painting operations without dismantling the housing. When such a large space is provided, it may be found desirable to employ slightly different reinforcing mechanism between the housing and the tank. One form of such mechanism has been illustrated in detail in Fig. 8 wherein the thrust screw 34a replaces the screw 34 employed in the first form. The screw 34a is shorter than the other and after passing through the tie bar 21, has its end disposed in a socket formed in the body of a tripod device 36a having legs 37a, the outer ends of which engage the exterior wall of the tank. By threading the screw into the tie bar an outward thrust will be imparted to the housing in the same manner as in the first form.

While but a single embodiment of the invention has been illustrated and described, the construction of the various parts may be varied to a considerable extent without departing from the spirit and scope of the invention as set forth in the appended claims.

What is claimed is:

1. In an insulating housing for gas holders of the type having a stationary section and vertical columns disposed in spaced relation therearound, a plurality of panels disposed around said stationary section between said columns, means for joining the edges of said panels and connecting the same to said columns, and thrust bolt means carried by said panels in spaced relation from said columns with one end of said bolt means in engagement with said stationary section, adjustment of said bolt means toward said stationary section serving to place said panels under outwardly directed stressing forces.

2. In an insulating housing for gas holders of the type having a stationary section and vertical columns disposed in spaced relation therearound, a plurality of panels disposed around said stationary section between said columns, insulating material carried by said panels, means for joining the edges of said panels and connecting the same to said columns, and thrust bolt means carried by said panels in spaced relation from said columns with one end thereof in engagement with said stationary sections, adjustment of said bolt means toward said stationary section serving to place said panels under outwardly directed stressing forces.

3. In an insulating housing for gas holders of the type having a stationary section and vertical columns disposed in spaced relation therearound, panel means positioned between said columns and comprising metallic frame members, sheet material secured to said frame members, tie bars

connecting groups of said panel means to form sections, means for securing the edges of said sections to said spaced columns, and thrust screw means carried by certain of said tie bars and engaged with the stationary portion of said gas holder to apply an outwardly directed stressing force to said panels.

4. In a gas holder of the type having a stationary tank section, vertically extending columns disposed in spaced relation around said tank section and a walkway supported by said columns adjacent to the upper portion of said tank section, insulating means for said holder comprising a plurality of panels disposed in vertical order between said columns, means for joining the edges of said panels and connecting the same to said columns and said walkway, and means carried by said panels and engaging said tank section between said columns, said means being adjustable to apply an outwardly directed stressing force to said panels at the points of connection thereof.

5. In a gas holder of the type having a stationary tank section, vertically extending columns disposed in spaced relation around said tank section and a walkway supported by said columns adjacent the upper portion of said tank section, insulating means for said holder comprising a plurality of panels disposed in vertical order between said columns, said panels including angular frames and sheet insulating material carried thereby, bracket means secured to said walkway between said columns, means for pivotally connecting certain of said panels to said bracket means, tie bar means connecting the edges of said panels to form sections, means for anchoring the edge portions of said sections to said columns, thrust bolts adjustably carried by said panel sections at spaced points, said thrust bolts being movable to engage the stationary tank of said holder and exert an outward force on said panels, and means for locking said bolts in positions of adjustment.

6. In a gas holder of the type having a stationary tank section, vertically extending columns disposed in spaced relation around said tank section and a walkway supported by said columns adjacent the upper portion of said tank section, insulating means for said holder comprising a plurality of panels disposed in vertical order between said columns, said panels including angular frames and sheet insulating material carried thereby, bracket means secured to said walkway between said columns, means for pivotally connecting certain of said panels to said bracket means, tie bar means extending between the frames of adjoining panels and holding the same in predetermined spaced relation between said columns, means for securing the edge portions of certain panels to said columns, insulating strips disposed in the spaces between adjoining panels, channel shaped flashing strips covering the joints between said panels and said insulating strips, and thrust bolts projecting through the spaces between said panels and engaging said stationary tank, adjustment of said thrust bolts serving to exert an outward pressure on said panels to resist exteriorly applied pressures.

7. In a gas holder of the type having a stationary tank section, vertically extending columns disposed in spaced relation around said tank section and a walkway supported by said columns adjacent the upper portion of said tank section, insulating means for said holder comprising a plurality of groups of superposed rectangular panels disposed in edge to edge relationship be-

tween said columns, the panels of each group being rigidly connected to form units, tie means connecting the edges of adjacent units and holding the same in predetermined spaced relation, means for securing the edges of certain units to adjacent columns, bracket means connecting the upper portions of said unit to said walkway, insulating strip means positioned in the spaces between adjoining units, flashing strip members covering the joints between said insulating strips and said units, thrust bolts carried by certain of said tie means and extending through the spaces between said units to engage said stationary tank section, said bolts being adjustable to impart outwardly directed forces to said panels to resist exteriorly applied forces, and lock nuts carried by said bolts to maintain the positions of adjustment thereof.

8. In a container of the type having vertically extending columns disposed in spaced relation around the body thereof, housing means for said container comprising a plurality of panels disposed in vertical order between said columns, means for joining the edges of said panels and connecting the same to said columns, means carried by said panels for cooperation with said container to exert outwardly directed thrust forces

15 to said panels at points spaced from said columns, and means provided with said housing for ventilating the space between said housing and said container.

9. In a gas container of the type having vertically extending columns disposed in spaced relation around the body thereof, means for protecting the exterior of said container comprising panel means extending between said columns and being spaced from said container body, means for securing the edges of said panels to said columns, and adjustable means carried by said panel means in spaced relation from said columns for engagement with said container body to exert outwardly directed forces on said panel means, said adjustable means being accessible from the exterior side of said protecting means.

10. In combination with a gas container of the type having a body and vertical columns disposed in spaced relation therearound, housing means extending between an adjacent pair of columns comprising panel means secured at the side edges to said columns, and means cooperating with said container body for exerting outward pressure to said panel means in spaced relation from said columns.

FERGUSON BARNES.
